UNITED STATES PATENT OFFICE

GEORGE EDGAR, OF PENSACOLA, FLORIDA

SEALING PLUG AND APPLYING MEANS THEREFOR

Application filed December 30, 1927. Serial No. 243,603.

This invention relates to a plug for use in connection with tube boilers and by means of which an effective seal is provided.

It is an object of the invention to furnish a device of this character which may be manipulated to quickly seal a leak after the latter is located and without the necessity of "cooling off" the boiler in order to permit of a temporary repair being effected.

10 A further object of the invention is that of furnishing a plug which may be introduced either through the fire door or back connection of a boiler without it being necessary that the fire of the latter be quenched, the invention 15 also contemplating a provision whereby the plug may be effectively positioned and applied.

An additional object is that of providing a device of this type, the parts of which will be 20 few in number and individually simple and rugged in construction, these parts being capable of ready assembly to furnish a plug which will be ready for virtually instant use and which will efficiently fulfill its purpose 25 until permanent repair may be effected.

With these and further objects in mind reference is had to the attached sheet of drawings in which :

Figure 1 is a sectional side view of one form 30 of plug and wrench embodying the improved construction of the present invention.

Fig. 2 is a rear end view thereof showing the wrench removed.

Fig. 3 is a forward end view of the plug. 35 Fig. 4 is an exploded perspective view of the several plug parts, and

Fig. 5 is a fragmentary sectional side view of the rear end of the expanding member with a slightly different form of wrench than that 40 shown in Fig. 1 applied thereto.

According to the present invention it is proposed, preferably, to employ a spool upon which a sleeve or body of packing, or sealing material as, for example, asbestos, is disposed 45 and which is expanded into sealing contact

with the rupture of, for example, a boiler tube and, in order that the plug of the present invention may be employed to seal a leak at any desired point throughout the length of the tube, this plug will, in its normal condition, be freely shiftable throughout the tube. 50

To this end a spool is preferably employed which, as shown, is formed of four arcuate segments each comprising a body 10 and a quadrantal end flange 11, the bodies being 55 thickened towards the flange portions and, when assembled, providing, in aggregate, a cylindrical mounting member with a substantially circular end flange and having a tapered, screw-threaded bore 12. With the 60 parts thus arranged a sleeve 13 is disposed thereon. As afore stated this sleeve may be formed of asbestos or any other suitable material having sealing qualities. This sleeve 65 may be held in position by employing a retaining member in association with the spool body. To this end plates 14 may be utilized secured, one to each of the arcuate segments 10 by means, for example, of screws 15 extending through bores in the plates and into 70 tapped and threaded openings formed at the rear ends of the spool sections.

Thus, it will be apparent that a plug is formed which comprises a mounting member upon which there is carried a body of sealing 75 material having a diameter larger than the flanges of the mounting member and such diameter being less than the diameter of a standard tube with which the plug is to co-operate. It is furthermore apparent that if 80 the sections of the spool body are forced outwardly, they will expand the sleeve 13 into sealing contact with the walls of a tube.

With a view to effecting such expansion a tapered spindle 16 is employed which is 85 formed with threads corresponding to the threads 12 and the tapering of which is at the same angle as the tapering of the spool bore. Accordingly, it will be obvious that, with the 90 parts in the position shown in Figure 1, a unit

is presented which embraces what might be termed a core (i. e., the spindle), a mounting member encircling the same and formed of several parts to be forced outwardly by such 5 spindle and a sleeve of packing or sealing material in turn associated with the mounting member and which sleeve will be forced into sealing contact with a surface, upon being expanded, incident to the outward movement 10 of the parts of the spool.

In order to move the spool parts in this manner, the spindle may have an irregular or, as shown, a squared shank 17 which, as in Figure 1, is formed with an interiorly threaded bore 18. A socket wrench, including a stem or handle portion 19, terminates in a socket 20 shaped to conform to the shank and the handle or stem portion 19 is hollow to receive a rod 21 which has one of its ends 20 threaded, as at 22, for engagement with the threads of the bore 18. Obviously, if the handle portion 19 is turned and the plug is retained against movement, the spindle will move inwardly, thus expanding the spool sections in order to effect the desired result. Likewise, if the spindle is turned in an opposite direction relative to the plug, the latter will contract and if the plug is to be shifted longitudinally, no accidental detachment of the spindle from the wrench will follow, in that this will be prevented by the rod 21.

35 In Figure 5 the head 17 of the spindle has been shown as being formed with recesses 23 which may be engaged by a spring-pressed
35 detent member 24 associated with the wrench
25. In this form of device it will be understood, likewise, that a turning of the wrench will expand or contract the plug parts, but that a detachment of the plug from the
40 wrench will not follow, under ordinary circumstances, incident to the retaining means employed. If, however, the plug is expanded into frictional and sealing contact with, for
45 example, a tube, it will be obvious that such detachment may be effected readily.

Obviously, a plug of this nature may be employed in numerous different associations. However, its value will be particularly apparent in connection with marine boiler work.

50 If, in such an installation, a tube springs a leak, it is not necessary that a ship remain idle for one or two days in order to cool off the boiler. Instead, a temporary repair may be effected while the boiler pressure remains up.

55 Obviously, any desired number of plugs may be used and they may, if desired, be positioned one beyond, and the other in advance of the leak in order to seal that portion of the tube which has become damaged; the remainder, or at least that end of the tube adjacent to the fire draft, still acting as a heating surface.

Thus, among others, the objects specifically aforementioned are achieved. It will be understood that numerous changes in con-

struction, re-arrangement of the parts and the character of materials employed, etc., might be varied in numerous aspects without departing from the spirit of the invention as defined by the claims.

Having described my invention, what I claim as new and desire to secure by Letters Patent is:

1. A plug including a sleeve of packing material, a spool for mounting the same, flanges at one end of said spool, flange portions removably secured to the other end of said spool and means for expanding said spool. 75

2. A device of the character described including, in combination, a sealing body, an expandible spool within said body, a core having screw threaded connection with said spool and to expand the same together with said sealing body, a wrench, cooperating surfaces forming a part of said wrench and core whereby the latter may be rotated with respect to said spool to effect expansion of the latter, and means independent of such cooperating surfaces for preventing an accidental detachment of said wrench from said core.

3. A device of the character described including, in combination, a sealing body, an expandable spool within said body, a core having screw threaded connection with said spool and to expand the same together with said sealing body, a wrench, cooperating surfaces forming a part of said wrench and core whereby the latter may be rotated with respect to said spool to effect expansion of the latter, said core being formed with a screw threaded recess and a screw threaded rod associated with said wrench and extending into said recess to prevent an accidental detachment of said wrench from said core. 95 100 105

4. A device of the character described including, in combination, a plurality of arcuate segments providing in aggregate a spool having a screw threaded bore, a sleeve of packing material enclosing said segments to retain the same in assembled relationship, a screw threaded spindle, said spindle and bore presenting cooperating tapered surfaces whereby upon relative rotation being effected, the segments of said spool will move outwardly to expand said sleeve, means for effecting relative rotation of said spindle and spool, and flange portions forming parts of said spool segments and extending to a point short of the periphery of said sleeve to retain the latter against displacement with respect to said spool.

5. A device of the character described including, in combination, a plurality of articulate segments providing in aggregate a spool having a screw threaded bore, a sleeve of packing material enclosing said segments to retain the same in assembled relationship, a screw threaded spindle, said spindle and bore

presenting cooperating tapered surfaces whereby upon relative rotation being effected, the segments of said spool will move outwardly to expand said sleeve, means for effecting relative rotation of said spindle and spool, and removable flange portions associated with said spool segments to prevent longitudinal movement of said sleeve with respect to said spool.

10 In testimony whereof I affix my signature.
GEORGE EDGAR.
